SIGNALING SYSTEM.

1,120,995.

Specification of Letters Patent.

Patent
REISSUED
Dec. 15, 1914.

Application filed January 23, 1914. Serial No. 813,892.

To all whom it may concern:

Be it known that I, CLARENCE E. BEACH, a citizen of the United States, residing at Binghamton, in the county of Broome and 5 State of New York, have invented certain new and useful Improvements in Signaling Systems, of which the following is a specification.

My invention relates to series circuit 10 alarm systems, in which there are a plurality of signal transmitting stations and a plurality of signal receiving stations on the same circuit. In a system of this kind it is often desirable to secure selective response of the 15 various receiving devices depending upon the wish of the person in charge at the transmitting station.

An object of my invention is to provide in 20 a series circuit switching mechanism associated with certain receiving and transmitting stations whereby said circuit may be adjusted, so that upon the operation of one of such transmitting stations all of the receiving devices in such circuit will not be 25 responsive to such operation, but the associated receiving devices (as for example, those on the same floor or in the same building) and certain other receiving devices (as for example, those provided for the local 30 fire department) will be responsive thereto.

Another object of my invention is to provide, in a series circuit, switching mechanism associated with certain receiving and transmitting stations whereby said circuit may be 35 adjusted, so that upon the operation of one of such transmitting stations the associated receiving devices (as for example, those on the same floor or in the same building) will be the only receiving devices 40 responsive thereto.

Another object of my invention is to provide, in a series circuit, switching mechanism consisting of a single switch associated with certain receiving and transmitting stations whereby said circuit may not only be 45 adjusted by means of said switch, so that upon the operation of one of such transmitting stations the associated receiving devices (as for example, those on the same floor or 50 in the same building) and certain other receiving devices (as for example, those provided for the local fire department) will be the only receiving devices responsive thereto, but whereby said circuit may also be adjusted, by means of said switch, so that upon 55

the operation of one of such transmitting stations, the associated receiving devices (as for example, those on the same floor or in the same building) will be the only receiving devices responsive thereto, and whereby said circuit may also be adjusted, by means of said switch, so that upon the operation of one of such transmitting stations all receiving devices in the entire system will be responsive thereto, including those provided for a city fire department and those on other floors or in other buildings. 60 65

Another object of my invention is to provide in a series circuit apparatus in connection with certain receiving devices whereby 70 the response of said receiving devices may be selectively controlled from transmitting stations located at a distance therefrom without running any extra wires between said receiving devices and said transmitting 75 stations which may be a long distance apart.

Another object of my invention is to utilize means provided for the purpose of receiving certain signals for indicating a decrease in the strength of the source of current supply to a point inconsistent with the best operation of the system, without interfering with the use of such means for indicating the signals for which it is intended, 80 by causing a single stroke bell to sound a multiplicity of strokes instead of only the usual single impulse, which might easily be missed. 85

Another object of my invention is to provide non-interference mechanism at the various stations, so adjusted that a fire signal has the right of way over a floor or drill signal and will not be interrupted thereby, but on the other hand, the floor or drill signal will be interrupted and the fire signal 90 transmitted to the fire departments without interference. 95

Another object of my invention is to provide non-interference mechanism which may be adjusted as between fire signals affecting 100 only the floor or building and the local fire department and fire signals affecting the entire system including the city fire department so as to enable the exercise of choice between possible interference at the local fire department station and a correct signal on the affected floor or a correct signal at the local fire department station and possible interference on the affected floor, giving the right of way to the signals considered to be 105 110

of most importance in any particular location.

For the purpose of illustrating my invention, I have shown in the accompanying drawing a circuit supplied with energy by the source 1, and connecting the various transmitting, receiving and controlling stations. There are shown two transmitting stations A and B, six receiving stations C, 5 D, E, F, G and H and two controlling stations J and K. While the controlling stations are herein described as if they were distinct from their associated transmitting stations, it will be obvious to one skilled in 10 the art that the mechanism of the controlling station might be located in or near the case containing the mechanism of the transmitting station.

Each controlling station is provided with 20 switch mechanism which includes the switch arm 2 and the contacts 3, 4 and 5 with any one of which said arm is adapted to engage. At controlling station J the pivot of arm 2 is connected to the main circuit at junction 6. One terminal of the resistance 7 is connected to contact 3 and one terminal of the resistance 8 is connected to contact 5. The other terminals of resistances 7 and 8 are connected together and then to the 25 main circuit at junction 9. At controlling station K the pivot of arm 2 is connected to the main circuit at junction 11. One terminal of the resistance 8 is connected to contact 5 and the other terminal of said resistance is connected to the main circuit at junction 10. Contact 3 is connected to an intermediate point on resistance 8. At both 30 stations contact 4 is blank. At controlling station J the switch arm 2 is shown in engagement with contact 4, this being the position in which all receiving devices will be operated by a transmitting station associated with this controlling station, while at controlling station K the switch arm 2 is 35 shown in engagement with contact 3, this being the position in which only the associated receiving devices will be operated by a transmitting station associated with this controlling station. At station J the value 40 of resistance 8 is such that when the shunt circuit through it is closed, the current in the rest of the system will be decreased to such an extent by the opening of the shunted contact springs that magnet 13 will 45 release its armature to open the circuit of the gong 12 associated therewith at station C while the current is not decreased to an extent sufficient to permit the retraction of the armatures of the gongs at stations F, 50 G and H. Resistance 8 at station K is of 55 similar value. The value of resistance 7 at station J and of the right hand portion of resistance 8 at station K is so low that when the shunt circuits including them are 60 closed, the current in the rest of the sys- 65

tem will be so little decreased by the opening of the shunted contact springs that the gongs in the rest of the system will not respond. The value of these resistances must be high enough so that the portion of the 70 total current flow which passes through the path shunted by these resistances will be sufficient to cause operation of the devices therein.

The receiving stations C, D, E, F, G and 75 H are provided with suitable receiving devices, such as the gongs 12. All of these gongs are so constructed that their armatures will not be retracted until the current through the magnets is very greatly decreased, it being a feature inherent in any 80 electromagnetic device that it will retain its armature in attracted position at a current strength considerably less than that required to move the armature into attracted 85 position. Receiving station C, representing the station for the local fire department, for example, is provided with additional equipment including the magnet 13 and the switch 14 which is connected in the circuit of 90 gong 12 at that station and is controlled by said magnet.

Magnet 13 is so adjusted that it will allow its armature to be retracted to open the circuit of its associated gong 12 whenever the 95 current is decreased by a break in the circuit in parallel with either resistance 8. The relative resistances of the magnet 13 and the magnet of the gong 12 associated therewith should preferably be such that when these 100 magnets are in parallel and the current flow in the circuit is decreased to a predetermined value such as might jeopardize the efficient operation of my system but not as greatly reduced as would be the case if the 105 entire line current was forced to pass through one of the resistances 8 through the separation of its associated contact springs 17 and 18, said magnet 13 will permit its armature to retract sufficiently to break the 110 circuit through gong 12 associated therewith and thereby permit said gong to sound, but in view of the increased current strength through magnet 13, said magnet would 115 upon the breaking of the shunt through gong 12, be sufficiently energized to again attract its armature and thus close the shunt through said gong and thus vibrate said armature so long as such current decrease continues.

At the transmitting stations A and B typical transmitting mechanism is shown, including the signal wheel 15, the signaling lever 16, the contact springs 17 and 18, together with the non-interference magnet 19, 120 and the armature structure 20 controlled thereby, said armature structure acting to hold the signaling lever in elevated position whenever the magnet 19 becomes deenergized while contacts 17 and 18 are closed.

When the switches are in the position shown in the drawing, the circuit is as follows: from source 1 to station C, passing through this station by two paths, the first 5 path comprising magnet 13, energizing this magnet and causing it to attract its armature to close switch 14 completing the second path through switch 14 and gong 12, energizing the magnet of the gong; thence to junction 13 6, through gong 12 at station D, through contact springs 17 and 18 and magnet 19 at station A, through gong 12 at station E, to junction 9, to junction 10 where the circuit divides into two paths, first 15 through sections F, B and G to junction 11 and second, from junction 10 to controlling station K, through right hand portion of resistance 8, to contact 3, to switch arm 2, to junction 11; here the two paths join and the 20 circuit passes through station H and back to source 1. The current normally flowing over this circuit energizes the magnets of all the gongs 12. If now the signal wheel 15 at station A is rotated the action of contact 25 springs 17 and 18 thereat will be to open and close the circuit above traced and all the gongs in the entire system will respond.

When the switch arm 2 at station J is placed on contact 3, the stations D, A and E 30 are shunted by resistance 7 and the rotation of the signal wheel 15 at station A will cause the response of only the gongs at stations D and E associated therewith, the value of resistance 7 being, as already explained, such that while this shunt is closed the separating of the springs 17 and 18 will not cause the other gongs to sound.

When the switch arm 2 at station J is placed on contact 5, the stations D, A and E 40 are shunted by resistance 8 and the rotation of the signal wheel 15 at station A will cause the response of the gongs at stations D and E associated therewith and also of the gong 12 associated with magnet 13 at station C, the value of resistance 8 being, as already explained, such that while this shunt is closed, magnet 13 will release its armature to open the circuit of the gong 12 associated therewith at station C whenever the springs 50 17 and 18 are open, while the current is not then decreased to an extent sufficient to permit the retraction of the armatures of the other gongs.

The operation of the switch mechanism at 55 controlling station K is similar to that of station J, the value of that portion of resistance 8 connected between contact 3 and junction 10 being approximately equal to that of resistance 7 similarly connected between contact 3 of station J and junction 9. Either method may be used, the distinction being immaterial to the operation of my invention.

The operation of the mechanism at station C is as follows: When the armature of

magnet 13 is retracted, all of the current in the circuit must pass through this magnet. However, as soon as the armature is moved to attracted position, magnet 13 is shunted by the magnet of the associated gong 12 and therefore receives only a portion of the total current. Hence it follows that while magnet 13 may be strongly energized while attracting its armature, when the shunt circuit is closed at contact 14, the energization 70 of magnet 13 is decreased and said magnet is thereafter in condition to release its armature upon a very slight diminution of the current. The operation of the mechanism at station C will make known a gradual deterioration 75 of the battery by the continued retraction and attraction of the armature of magnet 13 and the consequent continuous ringing of the gong 12 associated therewith. If a transmitting station should be operated even under this condition, the alarm would still be satisfactorily received.

The operation of the non-interference mechanism under the condition of more than one box being pulled at or about the same time will now be described. When two controlling stations have their switch arms 2 on contact 3 at each station, a transmitting station associated with one controlling station may be operated to transmit its alarm to the receiving stations associated therewith, and at the same time a transmitting station associated with the second controlling station may be operated to transmit its alarm to the receiving stations associated 90 with said second station, without either interfering with the other. If the controlling stations have their switch arms 2 on their respective contacts 4, thus forming the usual series circuit, the non-interference magnets 95 operate, in the manner well known in the art, to give the control of the circuit to the transmitting station which first has the line open while another has it closed. If one controlling station has its switch arm 2 on contact 3, as for a floor drill signal, and another controlling station has its switch arm 2 on contact 4, as for a general fire signal, the fire signal has the right of way and will hold back the floor signal if the 100 floor signal is operated while the fire signal is being transmitted, while if the fire signal is operated while the floor signal is being transmitted, the floor signal will be interrupted and the gongs formerly responding thereto will thereafter respond to the fire signal.

If one controlling station has its switch arm 2 on contact 4 and another controlling station has its switch arm 2 on contact 5, the result obtained when two boxes 115 are operated at the same time will depend upon the adjustment of the non-interference armature and either of two effects may be obtained, as follows: If the non-interference armature is adjusted so as to be re- 120

tracted at a comparatively high value of the current passing through its magnet and two stations are operated under these conditions, the station first having its contacts open while another has its contacts closed will obtain control of the line. With the same adjustment of the armatures, and two controlling stations each having their switch arms 2 on their respective contacts 5, the result will be the same, one station taking and holding control of the circuit.

In either of the above cases, if a transmitting station whose associated controlling station has its arm 2 on its contact 5 was the one which lost control of the circuit, there might be one or two blows upon the gongs associated with that controlling station and the rest of the signal from that station would be lost, while the local fire station C 20 would receive a correct signal from the station which prevailed. If, on the other hand, it is deemed that the importance, under these circumstances, of assuring the immediate transmission of the signals, from 25 both such stations to their respective groups of gongs outweighs the importance of assuring the receipt of the distinctive signal of one of such stations at station C, the non-interference armatures should be adjusted 30 so that they will be retracted only at a comparatively low value of the current passing through their magnets, then if the transmitting stations of two controlling stations each having their switch arms 2 on their 35 respective contacts 5 were pulled, both stations would operate station C. With this adjustment, the operation of a transmitting station whose associated controlling station had its arm 2 on its contact 4 would stop a transmitting station whose associated controlling station had its arm 2 in its contact 5 and transmit its own signal, thus at station C and the stations associated with the second controlling station, a partly transmitted 40 signal might be interrupted to give the more important fire signal right of way.

In the use of non-successive transmitting devices with my invention, preference may thus be exercised through the adjustment of 50 the non-interference magnets either to insure the transmission of a complete fire signal to the receiving devices provided for the local fire department or to the receiving devices on the affected floor.

55 If so-called "succession" transmitting devices are employed, the non-interference armatures should be adjusted so as to be retracted at a comparatively high current value and in this event, while the more important signal would always be given right of way and a less important signal of one of two equally important simultaneously started signals would be delayed, no signals would be lost.

65 It is obvious that in utilizing my inven-

tion other stations similar to any of those I have described may be located at any desired point in the circuit.

What I claim is:

1. In an electrical signaling system, a receiving device H responsive only to relatively large current changes, a receiving device C responsive to relatively small current changes, a transmitting device, one or more other receiving devices, two resistances, and means for connecting either resistance in shunt to said transmitting device and said other receiving devices, so constructed and arranged that when one resistance is so connected said transmitting device 70 may cause said relatively small current change and when the other resistance is so connected said transmitting device may cause a current change less than said relatively small change.

2. In an electrical signaling system, a receiving device H responsive only to relatively large current changes, a receiving device C responsive to relatively small current changes, a transmitting device, one or more other receiving devices, two resistances, and means for connecting either resistance in shunt to said transmitting device 80 and said other receiving devices.

3. In an electrical signaling system, a receiving device responsive only to relatively large current changes, an electro-magnet, a shunt to said electro-magnet, a receiving device in said shunt, a switch in said shunt controlled by said electro-magnet whereby 90 said receiving device is rendered responsive to relatively small current changes, a transmitting device, one or more other receiving devices, a resistance, and means for connecting said resistance in shunt to said transmitting device and said other receiving devices, so constructed and arranged that when said resistance is so connected said transmitting device 100 may cause said relatively small current change.

4. A series circuit including a current source, a transmitting device so connected in said circuit as to be adapted to formulate a distinctive signal consisting of a series of relatively small current changes in the current flow through said circuit, and an electro-magnet, a shunt around that portion of the series circuit including only said magnet, a receiving device in said shunt responsive only to comparatively large current changes, and a switch in said shunt adapted to be so controlled by said electro-magnet as to render said receiving device responsive to signals so formulated by said transmitting device, said current source and said 115 shunt being connected through said series circuit only.

5. In an electrical signaling system, an electromagnet, a shunt to said electromagnet, a receiving device in said shunt, a 120

switch in said shunt controlled by said electromagnet, a transmitting device, other receiving mechanism, a resistance, and means for connecting said resistance in shunt to said transmitting device and said other receiving mechanism.

6. In an electrical signaling system, an electromagnet, a shunt to said electromagnet, a receiving device in said shunt, a switch in said shunt controlled by said electromagnet, such construction and arrangement that said receiving device will be responsive to relatively small current changes, a receiving device responsive only to relatively large current changes, a transmitting device, other receiving devices, a resistance, and means for connecting said resistance in shunt to said transmitting device and said other receiving devices.

7. In an electrical signaling system, an electromagnet, a shunt to said electromagnet, a receiving device in said shunt, a switch in said shunt controlled by said electromagnet, such construction and arrangement that said receiving device will be responsive to relatively small current changes, a receiving device responsive only to relatively large current changes, a transmitting device, other receiving devices, two resistances, and means for connecting either resistance in shunt to said transmitting device and said other receiving devices.

8. In an electrical signaling system, an electromagnet, a shunt to said electromagnet, a receiving device in said shunt, a switch in said shunt controlled by said electromagnet, such construction and arrangement that said receiving device will be responsive to relatively small current changes, a receiving device responsive only to relatively large current changes, a transmitting device, other receiving devices, a resistance, and means for connecting said resistance in shunt to said transmitting device and said other receiving devices, so constructed and arranged that when said resistance is so connected said transmitting device may cause said relatively small current change.

9. In an electrical signaling system, an electromagnet, a shunt to said electromagnet, a receiving device in said shunt, a switch in said shunt controlled by said electromagnet, such construction and arrangement that said receiving device will be responsive to relatively small current changes, a receiving device responsive only to relatively large current changes, a transmitting device, other receiving devices, two resistances, and means for connecting either resistance in shunt to said transmitting device and said other receiving devices, so constructed and arranged that when one resistance is so connected said transmitting device may cause said relatively small current change and when the other resistance is so

connected said transmitting device may cause a current change less than said relatively small change.

10. In an electrical signaling system, a receiving device responsive only to relatively large current changes, an electromagnet, a shunt to said electromagnet, a receiving device in said shunt, a switch in said shunt controlled by said electromagnet whereby said receiving device is rendered responsive to relatively small current changes, a plurality of transmitting devices, one or more receiving devices associated with each transmitting device, and means whereby each transmitting device may be operated either to cause response of all the receiving devices or only of its associated receiving devices and said receiving device responsive to relatively small current changes.

11. In an electrical signaling system, a receiving device responsive only to relatively large current changes, an electromagnet, a shunt to said electromagnet, a receiving device in said shunt, a switch in said shunt controlled by said electromagnet whereby said receiving device is rendered responsive to relatively small current changes, a plurality of transmitting devices, a resistance and one or more receiving devices associated with each transmitting device, and means whereby each transmitting device and its associated receiving devices may be shunted by the associated resistance, so constructed and arranged that when said resistance is so connected said transmitting device may cause response of its associated receiving devices and said receiving device responsive to relatively small current changes.

12. In an electrical signaling system, a receiving device responsive only to relatively large current changes, an electromagnet, a shunt to said electromagnet, a receiving device in said shunt, a switch in said shunt controlled by said electromagnet whereby said receiving device is rendered responsive to relatively small current changes, a plurality of transmitting devices, a resistance and one or more receiving devices associated with each transmitting device, and means whereby each transmitting device and its associated receiving devices may be shunted by the associated resistance.

13. In a series circuit, a receiving device responsive only to relatively large current changes, a receiving device responsive to relatively small current changes, a transmitting device, one or more other receiving devices associated with said transmitting device, a movable switch member connected with said series circuit at one side of said transmitting device and said associated receiving devices, a contact cooperating with said movable member to connect a relatively high resistance from said one side to the

other side of said transmitting device and said associated receiving devices, and a second contact coöperating with said movable member to connect a relatively low resistance between said sides, said movable member being arranged to open its circuit when disengaged from both of said contacts.

14. In a signaling system having a normally closed series circuit including an electro-magnet, signal transmitting devices and such circuit connections that said transmitting devices may be partially shunted out without shunting said electro-magnet; a shunt around that portion of said series circuit including only said magnet, a receiving device in said shunt, and a switch in said shunt controlled by said electro-magnet.

15. In a signaling system having a normally closed series circuit including an elec-

tro-magnet, signal transmitting devices and such circuit connections that said transmitting devices may be partially shunted out without shunting said electro-magnet; a shunt around that portion of said series circuit including only said magnet, a receiving device in said shunt, and a switch in said shunt controlled by said electro-magnet, all so proportioned and adjusted that said receiving device is rendered responsive to the current changes incident to the operation of said partially shunted out signaling devices.

In witness whereof, I have hereunto subscribed my name, this 22nd day of January, A. D., 1914.

CLARENCE E. BEACH.
